[57] CLAIM

The ornamental design for a handle for a pizza cutter and server, as shown and described.

DESCRIPTION

FIG. 1 is a top, front, right side side perspective view of a handle for pizza cutter and server showing my new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a rear elevational view thereof;

FIG. 7 is a front elevational view thereof;

FIG. 8 is a top, front, right side perspective view of an alternate embodiment of that shown in FIG. 1;

FIG. 9 is a bottom plan view of that shown in FIG. 8;

FIG. 10 is a top plan view of that shown in FIG. 8;

FIG. 11 is a right side elevational view of that shown in FIG. 8;

FIG. 12 is a left side elevational view of that shown in FIG. 8;

FIG. 13 is a rear elevational view of that shown in FIG. 8; and

FIG. 14 is a front elevational view of that shown in FIG. 8.

The broken line showing of the pizza cutter and server are for illustrative purposes only.
